CLAIM

The ornamental design for a protective holder for portable electronic devices with auxiliary battery and charger, as shown and described.

DESCRIPTION

FIG. 1 is a front view of the protective holder for portable electronic devices with auxiliary battery and charger;

FIG. 2 is a top plan view thereof;

FIG. 3 is a bottom plan view thereof;

FIG. 4 is a right side view thereof;

FIG. 5 is a left side view thereof;

FIG. 6 is a rear view thereof;

FIG. 7 is a front perspective view thereof; and,

FIG. 8 is a front perspective view thereof, in an opened position.
